UNITED STATES PATENT OFFICE.

CARL WILKE, OF RECKLINGHAUSEN, GERMANY, ASSIGNOR TO CARL STILL, OF RECKLINGHAUSEN, GERMANY.

REGENERATIVE COKE-OVEN.

1,185,961.

Specification of Letters Patent. Patented June 6, 1916.

Application filed June 11, 1914. Serial No. 844,495.

To all whom it may concern:

Be it known that I, CARL WILKE, a subject of the German Emperor, residing at 21 Kaiserwall, Recklinghausen, Germany, have invented certain new and useful Improvements in Regenerative Coke-Ovens, of which the following is a specification.

This invention relates to regenerative coke ovens of the type constructed upon a foundation or sub-structure formed of arched passageways, said passageways being of sufficient area as to permit of the passage of the workmen or attendants in the performance of their work incident to the operation of said coke ovens, the invention having for its object to provide means arranged within these passageways whereby the heat radiated from the upper part of the passageways can be imparted to the air for combustion, and at the same time allow the lower part of said passageways, which are used by the attendants, to be retained at a proper and convenient temperature.

In coke ovens of the type mentioned herein, and which are adapted for the exhaustion of the air stored in the upper part of the foundation arches or passageways, the air is withdrawn therefrom at several suitable points and conducted either directly into the interior of the masonry of the ovens, or else into specially constructed conduits arranged in the foundations for conveying or leading the same away. In these cases, each arched passageway forms only a single chamber from the upper part of which the warm air is withdrawn and conducted away. According to this invention, however, the arched passageways are each sub-divided into an upper and lower chamber by horizontally arranged plates, acting as partitions, which plates form with the upper part of said passageways, channels or conduits for conducting the air to be withdrawn, and said plates or partitions also serving as the ceiling of the lower part of said passageways and providing means of insulation against radiation of heat from the upper part of the foundation arches toward the lower part thereof which is to be used by the workmen. Further objects and advantages will appear in the following description, it being understood that various changes in form, proportions and minor details of construction may be resorted to within the scope of the appended claims.

The invention is illustrated in the accompanying drawings, in which—

Figure 1 is a longitudinal section through a battery of regenerative coke ovens showing the application of my invention, said section being taken on the line A—B of Fig. 2; Fig. 2 is a transverse section of the same taken on the line C—D of Fig. 1, and Fig. 3 is a sectional view taken on the line E—F of Fig. 1, and showing the reversing valve arrangement for the regenerators.

Referring to the drawings *a* represents the coking chambers alternating with the adjacent heating flues *b*, the same being constructed and arranged above the arched passageways *c* of the foundation, which, in the present instance, are supposed to be built parallel to the longitudinal direction of the oven chambers. Beneath the heating flues *b* the gas distributing channels *d* are situated, and beneath the oven chambers *a* are located the air distributing channels *e*. The gas channels *d* receive heating gas from the two gas mains *g* which are located in the foundation of the ovens and distribute the gas into the single heating flues through the nozzles *f*, each of the latter being made accessible from the arched passageways *c* by means of a tube *h* arranged beneath the nozzle in the vertical axis of the latter. The air distributing channels *e* are connected with the heating flues *b* by means of passages *i*, and communicate with the regenerators *r* by means of channels *k*, the regenerators *r* arranged outside of the oven foundation along the whole length of the battery. Parallel to the regenerators *r* are the collecting channels *l* and *m*, likewise extending the whole length of the battery.

All of the arched passageways *c* are provided, according to this invention, with horizontal plates or partitions *s*, which extend across the foundation, and which are provided intermediate their ends (see Fig. 2) with openings *t* through which the air is drawn. The plates or partitions *s* are arranged in close proximity to the spring of the arches of the passageways *c* and divide said passageways into an upper chamber *u* and a lower chamber adapted for the use of the workmen or attendants. The plates *s* are preferably constructed of non-conducting material, such as plaster of Paris, etc., and are supported by lateral projections *x* (see Fig. 1) provided along the walls of the

passageways *c*. The upper chambers *u*, formed by the plates *s* and that portion of the arched passageways above the same, are in direct communication with the collecting channels *l* along the whole length of the oven battery by means of openings *v*. At one end of the battery, the collecting channels *l* communicate with channels *n* which are situated in plan view, at a right angle to the said collecting channels *l*; and in like manner, the collecting channels *m*, which are arranged parallel to the channels *l*, communicate with channels *o*. In the center of the front wall of the oven battery (see Fig. 3) the channels *n* and *o* are placed into communication one with the other, and at this point is arranged a reversing valve *q* for the regenerators. Beneath this point is arranged a connection between the channels 20 and a waste gas flue *p* leading to the chimney.

When operating the coke ovens, the air in the lower accessible part of the arched passageways *c*, is withdrawn therefrom through the openings *t* arranged in the plates or partitions *s*, and is conveyed through the chambers or conduits *u* arranged above said plates, whereupon the air is then conducted through the openings *v* into the collecting channels *l*. From these channels *l* the air is then conveyed through the adjoining channels *n*, arranged along the front wall of the oven battery, to the reversing valve *q* and through this valve, according to its position, into either one or the other of the two collecting channels *m* of the regenerators *r*. As shown in the drawings (see Fig. 3), the reversing valve is so arranged as to conduct the air into the left hand channel *m*. From the channel *m* just referred to the air is distributed to the regenerator *r* which is arranged to communicate with said channel *m*, and is highly heated in this regenerator which has been previously brought to a high temperature during the antecedent period of operation by the hot waste products of combustion passed through it, and is then conducted through the channels *k* into the air distributing channels *e* arranged beneath the oven chambers, so as to be distributed through the passages *i* to the single heating flues of one-half of the heating walls. In these heating walls the combustion of the heating gas simultaneously introduced by the gas distributing channels *d* and the nozzles *f*, takes place, whereupon the products of combustion are conducted through the upper horizontal passage of each heating wall and conveyed downward into the heating flues of the other half of the heating walls to the distributing channels in communication therewith, and from thence to the regenerator *r* arranged at the opposite end of the oven, and afterward through the channels *m*, *o* and *p*, and finally to the chimney.

After a certain period, the operation is reversed in the usual manner by means of the reversing valve *q*, and the other regenerator is used for heating the air, while the one first mentioned herein receives the waste products of combustion and is again brought to the requisite temperature. 70

The particular arrangement herein referred to for exhausting the air from the arched passageways and conducting the same to the regenerators, involves various important advantages. The improvements insure by simple means a very effective pre-heating of the air prior to its entrance into the regenerators, while at the same time permanently maintaining a convenient temperature in the lower accessible parts of the arched passageways in the foundation. As will be readily understood, the arches forming the crowns of the tunnels or passageways are the portions of the foundation or substructure, wherefrom the surplus heat of the ovens is radiated into said tunnels or passageways in a downward direction. By dividing these arches into upper and lower chambers by means of a horizontal plate or partition as above referred to, and thus forming conduits for conducting the air to be withdrawn, the total volume of air drawn in must first pass along the entire length of the heat radiating surface of the arches prior to its entrance into the regenerators. Thus it will be seen that by this means the heat from these highly heated surfaces is effectively transferred to the air continuously passing through the conduits or chambers arranged above the plates or partitions, and thereby the pre-heating of the air is assured. Furthermore, the horizontal plates or partitions beneath the arches which can be made of non-conducting material without additional cost, form an effective means of insulation against radiation of heat from the upper heated parts of the foundation arches toward the lower accessible parts of the passageway. This advantage is considerably increased by the fact that the air in the upper conduit or chamber represents, by itself, a very effective means of insulation. In consequence, a low air temperature is constantly maintained in the lower chambers of the foundation arches or passageways, which is of the utmost importance when considering that these passageways are used to a great extent by the workmen or attendants, and which considerably facilitates their work in attending to the gas main and the burners of each single heating flue. The present invention therefore avoids the useless withdrawal of surplus heat from the foundation masonry of the ovens to the lower accessible chambers adapted for use in regulating the ovens, and all inconveniences associated therewith, and the heat radiated from the ovens in a downward direction is imparted 80 85 90 95 100 105 110 115 120 125 130

to the air to be passed to the regenerators, thus rendering the fullest amount of the surplus heat useful for the working of the ovens.

6 Having thus described my invention what I claim and desire to secure by Letters Patent is:—

1. In combination with regenerative coke ovens constructed upon a sub-structure formed of arched passageways, a plate or partition arranged in the upper part of each passageway and forming with the arch structure above it a conduit through which air is conveyed and pre-heated prior to its 10 passage through the regenerators.
2. In combination with regenerative coke ovens constructed upon a sub-structure formed of arched passageways, a plate or partition of non-conducting material arranged in the upper part of each passageway for forming a means of insulation against radiation of heat from the upper heated parts of the foundation arches toward the lower parts thereof.
- 25 3. In combination with regenerative coke

ovens constructed upon a sub-structure formed of arched passageways, a plate or partition arranged in the upper part of each passageway and forming with the arch structure above it a conduit through which 30 air is conveyed and pre-heated prior to its passage through the regenerators, said plates being provided with openings through which the air contained in the spaces below the partition plates is adapted 35 to be drawn.

4. In combination with regenerative ovens, constructed upon a sub-structure formed of arched passageways, means arranged in the upper part of each passageway for preventing the direct radiation of heat from the upper part of the passageways to the lower part thereof.

In testimony whereof I have affixed my signature in presence of two witnesses.

CARL WILKE.
